UNITED STATES PATENT OFFICE.

DAVID S. KENNEDY, OF BROOKLYN, NEW YORK, ASSIGNOR TO MERGENTHALER LINOTYPE COMPANY; A CORPORATION OF NEW YORK.

APPARATUS FOR PREPARING TYPE-BARS OR SLUGS FOR USE IN PRINTING-FORMS.

1,300,846.

Specification of Letters Patent. Patented Apr. 15, 1919.

Original application filed July 2, 1915, Serial No. 37,664. Divided and this application filed November 21, 1916. Serial No. 132,541.

To all whom it may concern:

Be it known that I, DAVID S. KENNEDY, a citizen of the United States, residing at Brooklyn, in the county of Kings and State of New York, have invented certain new and useful Improvements in Apparatus for Preparing Type-Bars or Slugs for Use in Printing-Forms, of which the following is a specification, reference being had therein to the accompanying drawing, and being a division of application Serial No. 37,664, filed by me on the 2nd day of July, 1915.

My invention is directed to an apparatus for preparing type bars or slugs, such as are cast in the commercial linotype machine, for use in printing forms.

Certain classes of work, such as advertising, illustrative matter and the like, require the use of cuts or printing plates in the form, and to meet this requirement, the plain portions of the slugs lying beyond their type characters are usually cut off to provide an open space in the form for the reception of a supporting block upon which the cut is mounted. This practice is objectionable, as it not only involves a number of different operations which entail much labor and loss of time, but in addition difficulty is experienced in locking up the form in the proper and exact manner required. Furthermore, the use of supporting blocks is undesirable, since they must be specially prepared to correspond to the particular style of plates to be inserted, and they can rarely be used after one service.

My invention is intended to overcome the above objections and aims to prepare the slugs so that they themselves may receive the printing plate and give it direct support. To this end, I propose to cut down or reduce the plain portions of the slugs so that the plate or cut may be placed thereon and supported at type height.

Referring to the drawings:

Figure 1 is a perspective view of my improved apparatus;

Fig. 2 is a sectional view of the rotary cutter employed therein;

Fig. 3 is a top plan view of a portion of the apparatus, showing a series of slugs in position to be acted upon by the cutter;

Fig. 4 is a similar view showing the slugs after they have been reduced by the cutter and with a printing plate in place thereon;

Fig. 5 is a section on the line 5—5 of Fig. 4;

Fig. 6 is a section on the line 6—6 of Fig. 3;

Fig. 7 is a perspective of a portion of the apparatus, showing the slugs immediately after they have passed the cutter;

Fig. 8 illustrates one of the finished slugs; and

Fig. 9 is a view of a different form of slug.

In the use of my improved apparatus, I preferably follow the method of procedure outlined in my earlier application before referred to. That is to say I assemble the cast slugs side by side upon a suitable support, then shift them endwise relatively to each other to bring the ends of their lines of type characters into transverse alinement, and thereafter cut down or reduce progressively or successively the plain edge portions of the slugs beyond the type characters. The slugs are subsequently locked up in the printing form, and in this condition their reduced portions will present a flat surface upon which the cut may be laid and supported at type height. The feature of preliminarily bringing the ends of the type lines into transverse alinement is particularly advantageous in facilitating the trimming of the slugs for the reception of cuts of irregular form or contour, it being understood that the slugs which are produced for use in connection with such cuts have their type lines of varying predetermined lengths to correspond. A whole series of such slugs may thus be trimmed at one operation, since the relative shifting of the slugs necessary to bring their type lines into transverse alinement will also locate their plain portions, which likewise vary in extent, in proper position for the trimming action.

This feature might also be advantageously employed in connection with the old practice, which involves the complete severing of the plain portions, as thereby a whole series of slugs having type lines of varying lengths could be cut off at one time, instead of requiring as many different operations as there are different lengths of line, as has been the practice heretofore.

Fig. 8 illustrates a slug Z prepared for use in a printing form in accordance with my invention. Here it will be seen that the

105

slug is provided with a line of type characters Z' extending partly along its edge, and with a recess Z^4 extending along the remainder of its edge, the recess being formed 5 by cutting down or reducing the plain edge portion Z^2 of the slug indicated by the dotted lines. When a number of such slugs are assembled side by side in the form, as in the manner indicated in Figs. 5 and 6, they 10 provide a plain and flat supporting surface corresponding in form to that of the printing plate to be mounted thereon, it being remembered that when the plate is of irregular form the recesses Z^4 will vary in length 15 on the respective slugs so as to adapt the outline of the supporting surface to correspond.

While my improved apparatus is particularly adapted to carry out the method above 20 noted and will hereafter be described with reference to such method, I wish it to be distinctly understood that my invention contemplates any method that may be followed in the use and manipulation of the apparatus now to be described.

As shown in Fig. 1, the slugs Z , just as they are cast in the linotype machine, are assembled side by side with their bottom edges resting upon a supporting table B , 30 which is arranged to slide horizontally in a flat bed plate A^1 supported in the framework A . The table B is provided with side and end flanges B^1 , which may be availed of to even up the slugs and to maintain them 35 in proper position.

When thus assembled, the slugs are shifted longitudinally to bring the ends of their type lines Z^1 up against a straight transverse bar or gage D , which is pivotally 40 mounted upon a pin D^1 supported in the bracket plate D^2 fixed to the sliding table B . The bar D thus positively and simultaneously effects the proper transverse alinement of the type lines at their ends, it being noted that said type lines are carried 45 by raised surfaces Z^3 which engage the bar. This alining action locates the plain edge portions Z^2 of the slugs beyond the bar and in the proper condition for the trimming 50 action, it being observed that, in the present instance, the slugs are of the same length but have type lines of different lengths and that consequently the plain portions are projected different distances beyond the alining bar, due to the relative shifting of the 55 slugs, as shown in Fig. 3. In this way, all the slugs are disposed so as to be trimmed at one operation and notwithstanding the fact that their plain portions vary in length 60 as just stated. When the slugs are thus disposed, they are pressed tightly together and held up against the end flange B^1 of the table by a clamping jaw B^2 carried thereby and operated by the usual devices B^3 .

65 In performing the trimming operation,

the table B is moved along the bed plate A^1 so as to carry the slugs sidewise as a whole past an overlying rotary cutter C , provided with peripheral and face cutting teeth C^1 and C^2 , respectively, and which thereby 70 trims down or reduces the plain portions Z^2 of said slugs progressively or successively, thus forming therein the recesses Z^4 for the insertion of the printing plate or cut Y , as before described. Fig. 6 shows the slugs as 75 they are about to pass beneath the cutter C and Fig. 7 shows them after they have passed thereby. The cutter is attached to the lower end of a vertical shaft C^4 (see Fig. 2) rotatably mounted in a sleeve C^3 , which is supported between bearing plates A^3 fixed to the free end of a bracket A^4 rising 80 from the framework A and spanning the bed-plate A^1 , as shown in Fig. 1. The shaft C^4 may be driven in any suitable manner; 85 in the present instance, it is provided at its upper end with a pulley C^9 connected by a belt C^{10} to a second pulley C^{11} fixed to the upper end of a driving shaft C^{12} receiving motion from some suitable source. 90

After the slugs have been trimmed in the manner just described, they are released from the action of the clamping jaw B^2 and shifted, if need be, so as to bring the ends of their body portions into transverse alinement, in the manner indicated in Fig. 4. When in this position the recesses Z^4 will be arranged so as to provide a flat supporting surface on the slugs corresponding in outline to the form or contour of the printing plate or cut and upon which it may be sustained at type height. It is not essential that the alinement of the slugs by their body portions be effected upon the table B , as illustrated in Fig. 4, as the same result would 100 be secured when the slugs are locked up in the form. The idea in this connection is that after the slugs are trimmed, they should be restored to the proper position for printing, when they will also be ready to 105 receive and support the plate or cut to be inserted.

As shown in the drawings, the position of the alining bar D is such as to bring the ends of the type lines close up to the cutter 115 C , so that the recesses Z^4 of the slugs will allow the plate inserted thereon to stand immediately adjacent to the ends of the type lines. However, in some instances it may be desired to locate the plate away from the 120 ends of the type lines, in which event the recesses Z^4 should be cut a corresponding distance therefrom. For this and other reasons, the alining bar D is laterally adjustable upon the supporting pin D^1 so that it 125 can be set at different distances from the cutter C , a screw D^8 being employed to hold the bar in its adjustable position. In this way, when the slugs are shifted longitudinally to bring the ends of the type lines up 130

against the bar D, a greater or less extent of their plain portions Z² will be presented to the action of the cutter according to the position of the bar.

- 5 Similarly, it may be desired in some instances to vary the depth of the recesses Z⁴, that is, to increase or decrease their depth to correspond to printing plates of different thicknesses. To secure this result, the sleeve C³, wherein the shaft C⁴ of the cutter is mounted, is adjustable vertically so as to locate the cutter at a higher or lower level as required. This adjustment of the sleeve C³ is effected by means of a surrounding 70
10 thumb-nut C⁶ connected thereto by means of screw threads. The nut is confined against endwise movement by means of a clip C¹³ secured to the bracket arm A⁴ and fitting in an annular groove in the nut, so
15 that by rotating the latter, the sleeve C³ will be raised or lowered to the proper extent. In order to indicate the extent of the adjustment, the nut is provided with a dial plate C⁷ coöoperating with a pointer C⁸ fixed
20 to the bracket A⁴.

As an alternative construction, the table B wherein the slugs are held may be adjusted toward and from the cutter C. Thus in Fig. 1 the bed plate A¹ is shown as
25 mounted to slide vertically in the framework A, its adjustment being effected by an operating handle A⁵ connected to one end of a shaft A⁶ mounted in bearings of the bed plate and geared to a vertical shaft A⁷
30 also mounted in fixed bearings of the bed plate and screw-threaded into the framework. The extent of adjustment is indicated by a dial plate A⁹ secured to the shaft A⁶ and coöoperating with a relatively fixed
35 pointer A¹⁰.

In Fig. 9 the slug Z is shown as having the shoulder at the end of the recess Z² undercut, as at Z⁵, so as to receive the beveled edge of a printing plate Y¹. When a
45 series of such slugs are assembled in the form, their undercut walls Z⁵ will overhang one edge of the printing plate and thus serve to hold it down in place upon the slugs. If desired, short blocks Z⁸ having undercut
50 lips Z⁷ on their upper edges may be employed to engage and overhang the opposite edge of the plate and hold it against displacement. In this instance, the two outermost slugs have their edges cut off to make
55 room for the insertion of the blocks. It will be understood that in providing slugs with such undercut lips, the only change required is in the form of the peripheral teeth C¹ of the cutter C, as by beveling the teeth.

60 While my invention is intended primarily to adapt the slugs for receiving and supporting a cut or printing plate, it should be understood that other uses may be made of it which will still be comprised within its spirit. It will frequently be desirable to re-

duce the plain portions of the slug so that they will stand below the printing surface,—for instance, to prevent ink being deposited thereon and carried onto the paper. In short, the invention will be useful in any 70 case where it is desired to cut down or reduce the height of the slug. Furthermore, it should be understood that my invention may be realized without necessarily following the exact steps which have been enumerated and described, and also without employing the precise form of mechanism shown except as limited by the appended claims. Many changes and variations therein will readily suggest themselves to those 80 skilled in the art without departing from the scope of my invention.

Having thus described my invention, its construction and mode of operation, what I claim and desire to secure by Letters Patent 85 of the United States is as follows:

1. In an apparatus for trimming slugs for the reception of cuts or printing plates, the combination of means for holding a series of slugs side by side, means independent 90 of the cut or printing plate whereby the ends of their type lines may be simultaneously brought into transverse alinement, and means for reducing or recessing the plain edge portions of the slugs beyond the type 95 lines.

2. In an apparatus for trimming slugs for the reception of cuts or printing plates, the combination of means for holding a series of slugs side by side, means independent of 100 the cut or printing plate whereby the ends of their type lines may be simultaneously brought into transverse alinement, and means for trimming the plain portions of the slugs beyond the type lines.

3. In an apparatus of the class described, the combination of means for holding a series of slugs with their edges exposed, and a cutting tool adapted to reduce or recess the exposed edges of the slugs, one of said 110 parts being movable relatively to the other in such direction as to subject the slugs successively to the action of the cutting tool.

4. In an apparatus of the class described, the combination of means for holding the 115 slugs side by side, means whereby the ends of their type lines may be simultaneously brought into transverse alinement to expose the plain edge portions beyond the type lines, a cutting tool adapted to reduce or 120 recess the exposed edge portions of the slugs, and means for adjusting the slug holding means and the cutting tool one toward and from the other to vary the extent of the cutting action.

5. In an apparatus of the class described, the combination of a support for holding a series of slugs side by side, a straight bar or gage to engage the ends of the type lines 125 on the slugs and positively effect the trans-

- verse alinement of said type lines, and a cutting tool adapted to act upon the plain portions of the slugs beyond the alining bar or gage.
5. In an apparatus of the class described, the combination of a cutting tool, a supporting table for holding a series of slugs side by side and movable transversely past the tool to subject the slugs to the cutting action thereof, and a transverse bar or gage to engage the ends of the type lines on the slugs and positively effect the transverse alinement of said type lines preparatory to the cutting action.
10. 6. In an apparatus of the class described, the combination of a cutting tool, a supporting table for holding a series of slugs side by side with their edges exposed, and a cutting tool mounted to rotate in fixed bearings and adapted to reduce or recess the exposed edges of the slugs, the said table being slidable in a direction at right angles to the length of the slugs to carry them sidewise past and present them successively to the cutting tool.
15. 7. In an apparatus of the class described, the combination of a cutting tool, a supporting table whereon the slugs are adapted to be arranged side by side and movable transversely past the tool to subject the slugs to the cutting action thereof, and a transverse bar or gage against which the ends of the type lines of the slugs may be positively and simultaneously alined preparatory to the cutting action, the said bar being adjustable 20 to different operative positions to expose a greater or less portion of the slugs to the action of the cutting tool.
25. 8. In an apparatus of the class described, the combination of a supporting table for holding a series of slugs side by side, a transverse bar or gage to engage the ends of the type lines on the slugs and positively effect the transverse alinement of said type lines, and a cutting tool past which the slugs are moved by the table and which is adapted to cut down or reduce the plain edges of the slugs beyond the alining bar or gage.
30. 9. In an apparatus of the class described, the combination of means for holding a series of slugs side by side, means to engage the ends of the type lines on the slugs and positively effect the transverse alinement of said type lines, and means for reducing or recessing the plain edge portions of the slugs beyond the type lines.
35. 10. In an apparatus of the class described, the combination of means for holding a series of slugs side by side, means to engage the ends of the type lines on the slugs and positively effect the transverse alinement of said type lines, and means for trimming the plain edge portions of the slugs beyond the type lines.
40. 11. In an apparatus of the class described, the combination of means for holding a series of slugs side by side, means to engage the ends of the type lines on the slugs and positively effect the transverse alinement of said type lines, and a cutting tool adapted to reduce or recess the plain edge portions of the slugs, the said cutting tool and the slug holding means being movable one relatively to the other in such direction as to subject the slugs successively to the action of the cutting tool.
45. 12. In an apparatus of the class described, the combination of a supporting table for holding a series of slugs side by side with their edges exposed, and a cutting tool mounted to rotate in fixed bearings and adapted to reduce or recess the exposed edges of the slugs, the said table being slidable in a direction at right angles to the length of the slugs to carry them sidewise past and present them successively to the cutting tool.
50. 13. In an apparatus of the class described, the combination of a cutting tool mounted to rotate in fixed bearings, a supporting table whereon the slugs are adapted to be arranged side by side, and means to engage the ends of the type lines on the slugs and positively effect their transverse alinement preparatory to the cutting action, the said supporting table being slidable in a direction at right angles to the length of the slugs to carry them sidewise past and present them successively to the cutting tool.
55. 14. In an apparatus of the class described, the combination of a cutting tool, a supporting table for holding a series of slugs side by side and slidable in a direction at right angles to the length of the slugs to carry them sidewise past and present them successively to the cutting tool, and the said table being constructed to permit the longitudinal shifting of the slugs thereon into the field of action of the cutting tool, and a straight bar or gage arranged to engage the ends of the type lines on the slugs when they are shifted longitudinally, and serving by such engagement positively to effect the transverse alinement of the type lines and to insure their location beyond the field of action of the cutting tool.
60. 15. In an apparatus of the class described, the combination of means for holding a series of slugs side by side, a cutting tool adapted to reduce or recess the plain edge portions of the slugs, and means for adjusting one of said parts toward and from the other to vary the extent of the cutting action.
65. In testimony whereof, I have affixed my signature.
- DAVID S. KENNEDY.
